[57] CLAIM

The ornamental design for a combined bottle and cap, as shown and described.

DESCRIPTION

FIG. 1 is a top, front and left side perspective view of a combined bottle and cap showing our new design;

FIG. 2 is a top plan view thereof;

FIG. 3 is a front elevational view thereof; the rear elevation being a mirror image;

FIG. 4 is a bottom plan view thereof;

FIG. 5 is a left side elevational view thereof;

FIG. 6 is a right side elevational view thereof; and

FIG. 7 is a perspective view of the bottle shown with the cap removed for clarity of illustration.

The broken line showing of a dispensing pump closure in FIG. 7 is for illustrative purposes only and does not form part of the claimed design.
